(57) **CLAIM**

The ornamental design for a collapsible storage bag, as shown and described.

DESCRIPTION

FIG. 1 is a perspective view of a storage bag according to the design;

FIG. 2 is a front view thereof;

FIG. 3 is a right side view thereof;

FIG. 4 is a left side view thereof, illustrated from the side opposite that of FIG. 3;

FIG. 5 is a top view thereof;

FIG. 6 is a bottom view thereof; and,

FIG. 7 is a rear view thereof.

The broken lines illustrate portions of the wheel structure, zipper track, and handles and form no part of the claimed design.

The mesh pattern is fragmentarily shown for convenience of illustration. It is understood that the pattern is uniformly continuous over the surfaces of the bag.
